Des. 198,558
Patented June 30, 1964

198,558

COMBINED VAPORIZER AND HUMIDIFIER

Clifford E. Grube, Chicago, Ill., assignor to Associated Mills, Inc., Chicago, Ill., a corporation of Illinois

Filed May 20, 1963, Ser. No. 74,973

Term of patent 14 years

(Cl. D83—1)

FIG. 1.

FIG. 2.

FIG. 3.

FIG. 4.

FIG. 5.

FIG. 6.

FIG. 7.

FIG. 8.

FIG. 9.

FIGURE 1 is a top plan view of a combined vaporizer and humidifier embodying my new design;

FIGURE 2 is a right side elevational view thereof;

FIGURE 3 is a front elevational view thereof;

FIGURE 4 is a rear elevational view thereof;

FIGURE 5 is a left side elevational view thereof;

FIGURE 6 is a bottom plan view thereof;

FIGURE 7 is a partial cross-sectional view taken on line 7—7 of FIGURE 1;

FIGURE 8 is a partial cross-section taken on line 8—8 of FIGURE 2; and

FIGURE 9 is a partial cross-section taken on line 9—9 of FIGURE 4.

I claim:

The ornamental design for a combined vaporizer and humidifier substantially as shown.
